UNITED STATES PATENT OFFICE.

SAMUEL KELLETT, OF SAN FRANCISCO, CALIFORNIA.

DESIGN FOR CENTER-PIECE.

Specification forming part of Design No. **8,015**, dated January 19, 1875; application filed January 2, 1875.
[Term of Patent 14 years.]

NO. 3.

To all whom it may concern:

Be it known that I, SAMUEL KELLETT, of the city and county of San Francisco, State of California, have invented and produced a new and original Design for a Center-Piece, reference being had to the accompanying photograph.

My new design consists of a drop or pendant, A, four inner figures, B, with bead C right and left. A shell, D, fills spaces between each quarter-section. The principal outer figure is in four bell-shaped scrolls, right and left, E E, raised shell F in center, fine scrolls, trimming round shell. A plain raised band, G, forms

outer edge with terminal on point. Between those last-described forms the plain ground of center-piece, on outer edge, curls round stems, on which are placed flowers, H H H, forming continuous wreaths of stems and flowers.

Having thus described my invention, what I claim as new and original, and desire to secure by Letters Patent, is—

The design for a center-piece, as shown and described.

SAML. KELLETT.
